UNITED STATES PATENT OFFICE.

JEREMIAH O'CONNOR, OF LEAVENWORTH, KANSAS.

LOCK.

SPECIFICATION forming part of Letters Patent No. 716,270, dated December 16, 1902.

Application filed April 19, 1902. Serial No. 103,682. (No model.)

To all whom it may concern:

Be it known that I, JEREMIAH O'CONNOR, a citizen of the United States, residing at Leavenworth, in the county of Leavenworth 5 and State of Kansas, have invented certain new and useful Improvements in Locks, of which the following is a specification.

My invention relates to improvements in locks; and the essential features of the invention may be said to consist in the peculiar arrangement and construction of the tumblers employed for operating the bolt.

The object of my invention is to provide a lock wherein access to the tumbler that throws the bolt is normally barred by a sliding key-hole plate and a secondary tumbler, which must be properly manipulated before the first-mentioned tumbler can be reached with the key.

20 The invention may be further said to consist in the novel arrangement and combination of parts hereinafter described, and pointed out in the appended claims.

In the accompanying drawings, which illustrate the invention, Figure 1 represents a plan view, partly in section, of the lock with the face-plate removed to show its interior mechanism. Fig. 2 is a longitudinal section taken on the line II II of Fig. 1. Fig. 3 is a 25 broken plan view of the lock with the sliding keyhole-plate in position thereon. Fig. 4 is a broken plan view of the lock with the sliding keyhole-plate removed. Fig. 5 is an enlarged sectional view of the secondary tumbler, taken on the line V of Fig. 2.

30 1 indicates the case, which may be of any suitable shape, and 2 is the face-plate, by the removal of which access may be had to the interior mechanism of the lock.

35 3 indicates the bolt, which is reciprocally located within the case and provided with curved notches 4, adapted to be engaged one at a time by a spring-actuated pin 5, for the purpose of assisting in retaining the bolt in a locked or unlocked position. The forward movement of the bolt is limited by an integral shoulder 6, adapted to contact with the end of the case, and its backward movement is limited by a stop 7, cast integral with the 40 inner side of the case. The opposite sides of the rear portion of the bolt are provided with

55 mortised tooth-racks 8, which mesh with toothed segmental tumblers 9 and 10, having stud-shafts 11, journaled in the casing. Tumbler 10 also has a rectangular post 12, adapted to be engaged by a key 13 when it is desired to operate said tumbler.

The above construction is not regarded as broadly new, and the essential features of the invention reside in the means employed 60 to baffle those not familiar with the construction of the lock from gaining access to the post 12. Said means consist of a sliding plate 14, secured to the face-plate by a screw 15 and pins 16, which operate in slots 17 in 65 the face-plate. The sliding plate is provided with a keyhole 18 and a rectangular lug 19, which extends through a slot 20 in the face-plate and limits the rotation of a secondary tumbler 21 by contacting with a lug 22 thereon. Said tumbler is journaled in the back and face plates of the case and has a transverse groove 23, which registers with the keyhole. Its shoulder 22 is normally held in 70 contact with lug 19 by a spiral spring 24, secured at its opposite ends to the tumbler and a post 25, projecting from the back of the casing. 75

As the secondary tumbler is intended simply as a blind to the uninitiated, its rotation, of course, will have no effect upon the bolt, 80 and in order to operate the latter it is necessary to first turn the tumbler one-quarter of a revolution, so that its groove will register with the slot 20 in the face-plate. Then by pushing the key to the right and downwardly 85 over the post after the end of the groove has been reached tumbler 10 may be turned to either throw or retract the bolt.

When the key is pushed to the right, as above described, the sliding plate moves there- 90 with and lug 20 engages groove 23 and prevents the spring 24 from turning and binding the secondary tumbler against the key, and thus render it difficult to push the latter over to post 12.

95 After the bolt has been operated and the key withdrawn that portion of slot 20 over the stud is immediately closed by the sliding key-hole-plate, which is retracted by coiled springs 26, and the secondary tumbler is rotated back 100 to its normal position by spring 24.

While I have not shown or described a

latch bolt or knob, it is obvious that the lock may be provided with the same when used on doors requiring a knob.

Having thus described my invention, what I claim as new, and desire to secure by Letters Patent, is—

1. In a lock, a tumbler for actuating the bolt, a slot in the case for gaining access to the tumbler, a sliding keyhole-plate adapted to normally close that portion of the slot over the tumbler, a lug on the sliding keyhole-plate which extends through the slot in the case, and a secondary tumbler which normally obstructs the path of the lug, substantially as described.

2. In a lock, a tumbler for actuating the bolt, a slot in the case for gaining access to the tumbler, a sliding keyhole-plate adapted to normally close that portion of the slot over the tumbler, a lug on the sliding keyhole-plate which extends through the slot of the case, a secondary tumbler which normally ob-

structs the path of the lug, and a groove in said tumbler to provide a path for the lug, substantially as described.

3. In a lock, a tumbler for actuating the bolt, a slot in the case for gaining access to the tumbler, a sliding keyhole-plate, springs for normally holding said plate over that portion of the slot above the tumbler, a lug on the sliding keyhole-plate which extends through the slot in the case, a secondary tumbler, a spring for normally holding the latter in a closed position to the path of the lug, a groove in the tumbler, and a key for turning the latter so the groove will be presented to the lug, substantially as described. 25 30 35

In testimony whereof I affix my signature in the presence of two witnesses.

JEREMIAH O'CONNOR.
